GAY L. TUFTS, OF ANAHUAC, TEXAS.

FOOT-REST.

1,113,719.

Specification of Letters Patent. Patented Oct. 13, 1914.

Application filed October 21, 1913. Serial No. 796,445.

To all whom it may concern:

Be it known that I, GAY L. TUFTS, a citizen of the United States, and a resident of Anahuac, in the county of Chambers and State of Texas, have invented a new and useful Improvement in Foot-Rests, of which the following is a specification.

My invention is an improvement in foot rests, and has for its object to provide a rest of the character specified, especially adapted for supporting the foot during the polishing of the shoe, and suitable for use in shops or in other places, wherein a support is provided, having means for clamping the shoe to the support, and a stand with which the support is so connected that it may be adjusted to the proper height for engagement of the shoe by the grips.

In the drawings:—Figure 1 is a side view of the improved rest with parts in section, Fig. 2 is a transverse vertical section, Fig. 3 is a section on the line 3—3 of Fig. 2, and Fig. 4 is a perspective view of the rest proper and connected parts.

The present embodiment of the invention comprises a standard 1 of tubular form, and of rectangular cross section, provided at its lower end with a flaring base 2, having openings 3 for receiving screws or the like to connect the standard to a floor or other fixed support.

The rest 4 for the foot is shaped to fit the sole of a shoe, as shown in Fig. 1, both as to contour, and as to supporting surface, and a transverse rib or ledge 5 is provided between the heel and the arch of the sole for engagement by the front of the heel of the shoe. The rest is connected to a tubular casing 6 of rectangular cross section, and shaped to fit closely within the standard 1, but not so closely that it will not move with respect to the standard. The said casing is provided with an opening 7 in its rear wall for a purpose to be presently described and the casing is connected to the foot rest 4 by means of converging arms 8 and 9. The said arms are integral with both rest and casing, and converge from the rest to the casing. The arm 8 is connected with the rest at the junction of the arch with the sole proper, while the arm 9 is connected with the rest at the junction of the heel portion with the arch. The arms as before stated, converge toward the casing to an in-

tegral connection with the front and rear faces thereof. Thus the rest is spaced above the upper open end of the casing and on account of the arch of the rest, there is a considerable space between the under face of the said arch and the top end of the casing. The casing is also provided with oppositely arranged longitudinal slots 10, at its upper end, the said slots being in the walls between those engaged by the arms 8 and 9. A slide bar 11 is arranged within the casing, the said bar being solid as shown, and shaped externally to fit the interior of the casing. The bar is provided with spaced lugs 12 at its upper end, and with an opening 13, intermediate its ends, and near its lower end. The opening 13 is in the opposite face of the bar from the opening 7 of the casing, and at the opening 13 of the bar, the casing 6 is provided with a longitudinally extending slot 14.

The standard 1 is provided with oppositely arranged pairs of spaced ears 15, and a Y-shaped clamping member is connected with each pair of ears. Each of the said members comprises a body 16, having a bearing arranged between a pair of ears 15 and pivoted to the ears by a pivot pin or rivet 18, which extends through registering openings in the ears and the bearing, and diverging arms 17, each of which is provided with a gripping jaw 19. At the junction of the body of each clamping member with its arms, one end of a link 20 is received between the arms and pivoted thereto by a pivot pin or rivet 21, and the other end of each arm is received between the lugs 12 of the slide bar, and is pivoted to the lug by a pivot pin or rivet 22. The inner ends of the links 20 lap alongside each other, and the lugs 12 are spaced apart a sufficient distance to permit the two ends to lie alongside each other between the lugs. The links are offset at their outer ends as shown, to permit the said outer ends to engage between the arms of the adjacent clamping member. The links 20 extend through the slots 10, before mentioned, of the casing 6, and it will be evident that when the slide bar 11 is moved vertically by mechanism to be presently described, the clamping members 16—17 will be moved toward and from the foot rest, the said jaws 19 being however, above the rest and in po-

sition to grasp the sole of the shoe at the arch of the sole, as shown in Fig. 1. Each of the said jaws extends transversely of the adjacent arm and is concave on its inner face in order that it may engage above and below the edge of the sole. The foot rest is moved longitudinally of the standard, that is, the said rest is adjusted with respect to the standard, by means of a lever 23. The lever is pivoted at 24 to a bracket 25, which extends laterally from the standard at the side adjacent to the opening 7 of the casing, and the inner end of the lever extends through an opening in the wall 15 of the standard and engages the opening 7 of the casing 6. The outer end of the bracket 25 is provided with an arc-shaped series of teeth 26, and the lever is provided with latch mechanism 27, for co-operating 20 with the teeth to hold the lever in adjusted position. A lever 28 is arranged at the opposite side of the standard from the lever 23, the said lever 28 being pivoted at 29 to a bracket 30 extending laterally from the 25 standard. The outer end of the bracket 30 is provided with an arc-shaped series of teeth 31, and latch mechanism 32 on the lever co-operates with the teeth to hold the lever in adjusted position. The inner end 30 of the lever extends through an opening in the standard wall and through a slot 14 to an engagement with the opening 13 of the slide bar. It will be noticed that the openings 7 and 13 flare inwardly, to permit the 35 free movement of the levers.

The operation of the device is as follows:—The standard may be arranged wherever desired, either singly or in pairs, and may be secured in rigid position by 40 means of screws or the like passing through the openings 3. The foot in the shoe is placed on the rest, with the gripping jaws in the dotted line position of Fig. 2. When the levers are in this position, the slide bar 45 is also in the dotted line position of such figure. To clamp the foot on the rest, the latch mechanism of the lever 28 is released from the teeth of the bracket 30, and the slide bar is moved downwardly, thus swinging the gripping members toward the shoe and causing the gripping jaws 19 to engage with the edge of the sole of the shoe at the arch. If the gripping jaws 19 do not exactly engage the sole, the casing 6 and the 50 rest 4 may be raised or lowered to bring the sole into register with the gripping jaws by means of the lever 23. When the jaws 19 are engaged with the sole, the shoe is held firmly from movement in any direction, thus 55 relieving the boot black of any care in regard to the proper position of the shoe and giving him free use of both hands. The person having his shoes polished is also relieved from any care in regard to the position of the foot, the shoe being firmly held

against movement in every direction. The shoe is easily released, merely by lifting the slide bar 11.

I claim:—

1. A device of the character specified, 70 comprising a tubular standard having a base, a foot rest, a casing slidable in the standard, the rest being connected with the upper end of the casing in spaced relation, and the said casing being tubular, a slide 75 bar within the casing and fitting the same, substantially Y-shaped gripping members hinged to the standard at opposite sides of the rest, each member comprising a body hinged to the standard and diverting arms, 80 the upper ends of the arms being at approximately a right angle to the body and extending inwardly toward the rest, each of the said arms having a gripping jaw for grasping the edge of the sole of a shoe, 85 a link connecting each member between the gripping jaws and its hinge connection with the slide bar, the casing being slotted at its upper end for receiving the links, means in connection with the standard at 90 one side thereof for raising and lowering the casing, and means in connection with the standard at the opposite side thereof for raising and lowering the slide bar, each of the said means comprising a lever, the 95 standard having a laterally extending bracket at each lever, said lever being pivoted to the bracket, the standard having an opening through which the inner end of the lever extends, and the bracket having 100 an arc-shaped series of teeth at its outer end, each lever having latch mechanism co-operating with the teeth of the bracket to hold the lever in position, the casing having an opening for receiving the inner end of 105 one lever and the slide bar having an opening for receiving the inner end of the other lever.

2. A device of the character specified, 110 comprising a tubular standard having a base, a foot rest, a casing slidable in the standard, the rest being connected with the upper end of the casing in spaced relation, and the said casing being tubular, a slide bar within the casing and fitting the same, 115 substantially Y-shaped gripping members hinged to the standard at opposite sides of the rest, each member comprising a body hinged to the standard and diverting arms, the upper ends of the arms being at approximately a right angle to the body and extending inwardly toward the rest, each of the said arms having a gripping jaw for 120 grasping the edge of the sole of a shoe, a link connecting each member between the gripping jaws and its hinge connection with the slide bar, the casing being slotted at its upper end for receiving the links, means in connection with the standard at one side thereof for 125

raising and lowering the casing, and means in connection with the standard at the opposite end thereof for raising and lowering the slide bar.

- 5 3. A device of the character specified, comprising a tubular standard having a base, a casing slidable in the standard and having rigid with the upper end thereof a foot rest, said casing being tubular, a slide 10 bar within the casing and movable longitudinally thereof, gripping jaws hinged to the standard at opposite sides of the rest for engaging the sole of the shoe to hold the shoe to the rest, a link connecting each 15 gripping jaw with the slide bar, the casing having slots at its upper end for receiving the links, means in connection with the standard at one side thereof for raising and lowering the casing, and means in connection 20 with the standard at the opposite side thereof for raising and lowering the slide bar.
4. A device of the character specified, comprising a tubular standard having a base, a casing slidable in the standard and having rigid with the upper end thereof a foot rest, said casing being tubular, a slide 25 bar within the casing and movable longitudinally thereof, gripping jaws hinged to the standard at opposite sides of the rest for engaging the sole of the shoe to 30

hold the shoe to the rest, a link connecting each gripping jaw with the slide bar, means in connection with the standard at one side thereof for raising and lowering the casing, 35 and means in connection with the standard at the opposite side thereof for raising and lowering the slide bar.

5. A device of the character specified, comprising a standard, a tubular casing 40 movable in the standard and having a foot rest at its upper end, gripping jaws hinged to the standard at its upper end for engaging the sole of the shoe on the rest, a slide bar movable in the casing and connected 45 with the gripping jaws to move the said jaws toward and from the rest when the slide bar is raised and lowered, means for moving the casing, and means for moving the slide bar. 50

6. A device of the character specified, comprising a standard, a foot rest having a depending casing movable in the standard, gripping jaws hinged to the upper end of the standard for gripping a shoe on the 55 rest, means for moving the jaws toward and from the shoe, and means for moving the casing longitudinally of the standard.
